US00D631066S

(12) **United States Design Patent**
Itadani et al.

(10) **Patent No.:** **US D631,066 S**
(45) **Date of Patent:** **** Jan. 18, 2011**

(54) **SEAL FOR A ROTARY SHAFT**

(75) Inventors: **Masatoshi Itadani**, Tokyo (JP); **Hisayuki Akagi**, Tokyo (JP); **Hideki Kawai**, Tokyo (JP); **Hideki Tomoto**, Tokyo (JP)

(73) Assignee: **Eagle Industry Co., Ltd.** (JP)

(**) Term: **14 Years**

(21) Appl. No.: **29/336,033**

(22) Filed: **Apr. 27, 2009**

(30) **Foreign Application Priority Data**

Nov. 26, 2008 (JP) 2008-030366

(51) **LOC (9) Cl.** **15-02**

(52) **U.S. Cl.** **D15/9**

(58) **Field of Classification Search** D15/7-9; D23/231, 232, 225; 417/410.1, 359, 415-416, 417/234, 321, 265, 405; 277/431, 377, 575, 277/908, 347

See application file for complete search history.
